UNITED STATES PATENT OFFICE.

FRED B. COREY, OF SCHENECTADY, NEW YORK, ASSIGNOR TO GENERAL ELECTRIC COMPANY, A CORPORATION OF NEW YORK.

EMERGENCY-BRAKE.

No. 823,992.

Specification of Letters Patent.

Patented June 19, 1906.

Application filed March 21, 1903. Serial No. 148,903.

To all whom it may concern:

Be it known that I, FRED B. COREY, a citizen of the United States, residing at Schenectady, in the county of Schenectady, State of New York, have invented certain new and useful Improvements in Emergency-Brakes, of which the following is a specification.

My invention relates to improvements in means for automatically controlling motors and power-actuated brakes in case of an emergency and is intended for use especially in connection with electrically-propelled vehicles or trains employing a braking system actuated by fluid-pressure.

15 The present invention relates to improvements in the emergency-brake apparatus set forth in my application, Serial No. 148,902, filed March 21, 1903, and comprises various novel features of construction and organization of parts, to be hereinafter described, and particularly pointed out in the claims.

20 In the accompanying drawings, which illustrate the preferred embodiment of my invention, Figure 1 is a front elevation of a specific form of motor-controller to which my invention has been applied, the casing-cover being removed and certain parts being shown broken away and in section. Figs. 2 and 3 are sectional plan views on the line 2 2 of Fig. 1, showing the emergency-valve-operating mechanism in its locked and operative positions, respectively. Fig. 4 is a sectional plan view on the line 4 4 of Fig. 1, and Fig. 5 is a 25 diagrammatic representation of an "automatic" air-brake system to which my invention may be applied.

30 Referring now to the drawings, A represents the back of a motor-controller casing, and E the operating-handle for the controller-cylinder B within said casing. The controller-cylinder B carries the usual contact-segments b and is geared by cog-wheels CC' to a shaft D, which runs up into the hub e of the operating-handle E. The hub is rotatable in 35 an opening in the cap-plate A' of the casing and is fastened to the shaft D by means of a set-screw d.

40 Rotatably mounted on the shaft D is a sleeve F, held yieldingly in its normal position by a helical spring F', which is connected at one end to the sleeve and at the other end to the shaft D, preferably by means of a collar

D', secured to said shaft. The sleeve F carries a cam f and lug f', Figs. 2 and 3, the latter serving as a stop by abutting against a stationary lug a' on the under side of the cap-plate.

45 Connected with the knob E' in the controller-handle is a pin e', which rests upon the long arm of the lever E', fulcrumed on the operating-handle E. A spring E' bears on the short arm of the lever and keeps the pin and knob normally raised. A toothed rocker E' also is fulcrumed on the operating-handle and engages with the short arm of the lever E'. The other end of the rocker E' engages 50 with a lug on a bolt G, slideable in a keyway in the shaft D and adapted to enter a notch in the upper end of the sleeve F and lock said sleeve to the shaft. This will occur whenever the knob E' is depressed, provided the controller-handle is in the position corresponding to the "off" position of the controller. The sleeve F is adapted to be rotated 55 with the shaft D so long as pressure is maintained on the broad knob E', on which the palm of the motorman's hand is adapted to rest while the controller-handle is being operated.

60 Adjacent to the shaft D within the controller is a rock-shaft H, carrying an arm h, which bears against the cam f, as shown in Figs. 2 and 3, whereby the movement of the sleeve F will rock the shaft H. Mounted on the shaft H is an arm h', carrying a block of insulation H', on which are mounted two connected spring-contact-fingers, which coöperate 65 with stationary contacts and form therewith a double-pole switch I for closing and opening the power-circuit when the shaft H is rocked. 70

75 RS represent the reversing-switch, W an interlocking device between said reversing-switch and the shaft D, and L indicates the insulating-casing containing the blow-out coil for the switch I.

80 Mounted within the controller-casing and operatively connected in the air-brake system is an emergency-valve which is adapted to apply the brakes in case the controller-handle is released in any of its operative positions. To apply the brakes when the so-called "automatic" air-brake system is employed, the emergency-valve exhausts the 85 train-pipe to atmosphere, and when the so-

called "straight" air-brake system is employed it connects the source of compressed-fluid supply to said train-pipe.

I have chosen to illustrate my invention in connection with the automatic air-brake system, and in Fig. 5 the train-pipe, which is connected to the brake-cylinder 7 and the auxiliary reservoir 8 through the customary triple valve 9, is indicated by 6. The said train-pipe 6 is connected to the source of compressed-fluid supply, here illustrated as a motor-driven air-compressor 10, through the engineer's valve 11 and the storage-reservoir 12. The emergency-valve P is connected, by means of the pipe 13, with the train-pipe and is adapted to exhaust said train-pipe to atmosphere through the port 14 to apply the brake.

The mechanism for operating the emergency-valve will now be described. Pivotally mounted on the back of the controller-casing A at p is a lever k, the lower end of which is adapted to impinge the valve-spindle k' and open the valve within said casing P. The upper end of said lever is so formed as to project into the path of a lug o, carried on the under side of the cam f. This lug o is adapted to strike the upper end of said lever k when the cam f is in its normal position, corresponding to the off position of the controller, and thereby operates to open the emergency-valve whenever the controller-handle is released in any position. In order to release the brakes by closing the emergency-valve, there is provided a rod 14, carried by the lugs 15 and 16, supported from the cap-plate of the controller. This rod 14 projects through the side of the controller-casing and has a knob 17 at its outer end. The inner end of said rod is adapted to strike a lug 18, mounted on the upper side of the cam f, and is normally maintained in the position shown in Fig. 2 of the drawings by means of the spring 19. When the rod 17 is moved inwardly against the action of the spring 19, it rotates the cam f and the sleeve F against the action of the spring F', and thus moves the lug o, so as to release the pressure on the valve-spindle k' and allow the emergency-valve to close.

The cam f is adapted to be held in the position shown in Fig. 2 by means of the bolt G, operated by the knob in the controller-handle, or it may be locked in said position by means of the rod 20, so as to allow the motorman to release the controller-handle without causing the brakes to be applied. This rod is also supported by the lugs 15 and 16 and projects through the sides of the controller-casing and has a knob 21 at its outer end. The inner end of said rod 20 is adapted to enter a recess 22 in the cam f only when the said cam is in the position shown in Fig. 2. The leaf-spring 23 is provided for the purpose of holding the rod 20 in either its "out"

or "in" position, said spring 23 engaging the notches 24 in the rod 20.

In the operation of this controller and emergency-valve when the motorman places his hand upon the operating-handle E he depresses the push-pin e' and forces the bolt G down into the notch in the sleeve F, provided the cam f is in its proper position. The bolt G will enter the said notch when the cam f is locked in the position shown in Fig. 2 by means of the rod 20; but if the sleeve F, carrying the cam f, is in such position that the lug o engages with the upper end of the lever k in such a manner as to cause the emergency-valve to open it is impossible to cause the bolt G to enter the slot in the sleeve F by depressing the knob E' until the rod 14 has been operated to move the said sleeve and cam from the position shown in Fig. 3 to that shown in Fig. 2. During the operation of these rods, as above described, the controller is not moved from its off position. With the bolt G engaging the notch in the sleeve F the rotation of the handle operates first to close the cut-out switch 1 by operating the rock-shaft H through the agency of the sleeve F and the cam f and then to control the motor-circuits by means of the cylinder B. Now so long as the knob E' in the handle E is depressed in either the off or any operative position of the controller the lug o will be maintained out of engagement with the lever k and the emergency-valve will remain closed; but provided the rod 20 is not in its locking position when the motorman releases the knob E' the sleeve F will be released and will be turned by means of the spring F', so that the lug o strikes the upper end of the lever k before the lug f' strikes the stop a' on the cap-plate. The emergency-valve is thereby operated to apply the brakes. Simultaneously with the operation of the emergency-valve the rock-shaft H is operated to open the motor-circuit at the cut-out switch 1. The emergency-valve-operating mechanism is now in the position shown in Fig. 3 of the drawings, and it is impossible to release the brakes by attempting to depress the knob in the controller-handle, since in this position the bolt G cannot enter the slot in the sleeve F. To release the brakes, it is necessary to operate the rod 14 against the action of the spring 19 to rotate the cam f, so that the lug o will be moved out of contact with the lever k and the lug f' will be moved away from the stop a'. In this position the bolt G can enter the slot in the sleeve F, and thus render the emergency-valve inoperative. When the motorman desires to leave the car, it is possible to lock the emergency-valve-actuating mechanism in such a position by merely pushing in the rod 20 until it engages the recess 22 in the cam f that the brakes will not be applied when the motorman releases the controller-handle.

The specific construction of the working

parts of the motor-controller herein shown and described forms no part of my present invention and is not claimed herein, since it forms the subject-matter of a copending application of F. E. Case, Serial No. 75,488, filed September 16, 1901. It is merely illustrated and described here to show how my invention may be applied to the type of controller ordinarily employed as a master-controller in train-control systems. It will be readily understood that the invention is not limited in its application to any specific form of controller.

Although I have shown and described my invention in connection with an automatic air-brake system—that is, a system in which the engineer's valve exhausts the train-pipe to atmosphere—it is evident that it is equally applicable to the so-called "straight" air-brake system.

The controlling-handle from which the emergency-valve is operated is not necessarily the operating-handle of the motor-controller, as herein shown and described, but may be the operating-handle of the engineer's valve or any other handle adapted for the purpose.

I aim to cover in the claims hereto appended all modifications both of the system and of the apparatus herein disclosed which do not involve a departure from the spirit and scope of my invention.

What I claim as new, and desire to secure by Letters Patent of the United States, is—

1. In combination, a controller having a shaft and an operating-handle, a power-actuated brake, a brake-controlling device, a member loosely mounted on said shaft for operating said brake-controlling device to cause the brakes to be applied, means for actuating said member, means for locking said member to said shaft, said latter means being arranged to unlock said member from the shaft when the controller-handle is released, and means for moving said member on said shaft to release the brake-controlling device.

2. In combination, a controller having a shaft and an operating-handle, a brake actuated by fluid-pressure, a valve for controlling said brake, a member loosely mounted on said shaft for operating said valve to cause the brakes to be applied, means for actuating said member, means for locking said member to said shaft, said latter means being arranged to unlock the said member from the shaft when the controller-handle is released, and means for moving the said member on said shaft to release the valve.

3. In combination, a controller having a shaft and an operating-handle, a brake actuated by fluid-pressure, a valve for controlling said brake, a member loosely mounted on said shaft for operating said valve to cause the brakes to be applied, a spring to actuate said member, means for locking said member to the shaft, said means being arranged to un-

lock the member from the shaft when the controller-handle is released, and means arranged to engage with said member when in its valve-operating position for moving said member on the shaft to release the valve. 70

4. In combination, a controlling-handle having a shaft operatively connected thereto, a brake actuated by fluid-pressure, a valve for controlling the operation of said brake, a sleeve loosely mounted on said shaft, means carried by said sleeve for operating said valve to apply the brake, actuating means for said sleeve, means for locking said sleeve to the shaft, said latter means being arranged to unlock the sleeve from the shaft when the controller-handle is released, and means for moving said sleeve into valve-releasing position. 75

5. In combination, a controlling-handle having a shaft operatively connected thereto, a fluid-pressure brake, a brake-controlling valve, a sleeve loosely mounted on said shaft and arranged to normally coöperate with said valve to apply the brake, actuating means for said sleeve, means for locking said sleeve to the shaft for movement therewith, said latter means being arranged to unlock the sleeve from the shaft when the controller-handle is released, and means for moving said sleeve into brake-releasing position. 90 95

6. In combination, a controlling-handle, a brake actuated by fluid-pressure, a valve controlling the operation of said brake, a sleeve loosely mounted on a shaft operatively connected with the handle, means for locking said sleeve to said shaft, means carried by said sleeve for operating said valve to apply the brake when said locking means is released, and means for holding said sleeve in position to prevent it from actuating said valve when said locking means is released. 100 105

7. In combination, a motor-controller, a handle for operating said controller, a brake actuated by fluid-pressure, a valve controlling the operation of said brake, a sleeve loosely mounted on the controller-shaft, means operated from the controller-handle for locking said sleeve to said shaft, means carried by said sleeve for operating said valve to apply the brake when said locking means is released, means for moving said sleeve into a position to operate said valve to release the brake, and means for holding said sleeve in the last-mentioned position so as to allow said locking means to be released without causing the brake to be applied. 110 115 120

8. In combination, a motor-controller, a handle for operating said controller, a brake actuated by fluid-pressure, a valve for controlling the operation of said brake, a sleeve mounted on the controller-shaft, means operated from a controller-handle for locking said sleeve to the controller-shaft, means carried by said sleeve for causing said valve to operate to apply the brake when the con- 125 130

troller-handle is released, and rods extending through the controller-casing for operating said sleeve to cause said brake to be released and for locking said sleeve in a position so that the controller-handle can be released without causing the brake to be applied.

9. In combination, a controller having a shaft and an operating-handle, a power-actuated brake, a brake-controlling device, a member loosely mounted on said shaft for operating said brake-controlling device to cause the brakes to be applied, means for actuating said member, means for locking said member to said shaft, said latter means being arranged to unlock said member from the

shaft when the controller-handle is released, and a device for moving said member on said shaft to release the brake-controlling means, the arrangement being such that the means for locking said member to the shaft is made ~~20~~ inoperative to again perform its locking function until said latter device is operated to move the said member into brake-releasing position.

In witness whereof I have hereunto set my ~~25~~ hand this 19th day of March, 1903.

FRED B. COREY.
